DESIGN FOR A COMBINED CAN PERFORATOR AND COOKY CUTTER

George Gregory Bricco, White Lake, Wis.

Application May 6, 1941, Serial No. 100,810

Term of patent 7 years

To all whom it may concern:

Be it known that I, George G. Bricco, a citizen of the United States, residing at White Lake, in the county of Langlade and State of Wisconsin, have invented a new, original, and ornamental Design for a Combined Can Perforator and Cooky Cutter, of which the following is a specification, reference being had to the accompanying drawing, forming part thereof.

Figure 1 is an elevational view of a combined

can perforator and cooky cutter, showing my new design.

Figure 2 is a similar view but taken substantially at right angles to Figure 1.

Figure 3 is a top plan view, and
Figure 4 is a bottom plan view.

I claim:

The ornamental design for a combined can perforator and cooky cutter, as shown.

GEORGE GREGORY BRICCO.
